UNITED STATES PATENT OFFICE.

IRVING A. WESTON, OF SYRACUSE, NEW YORK.

MASSAGE INSTRUMENT.

No. 827,133.

Specification of Letters Patent.

Patented July 31, 1906.

Application filed February 26, 1904. Serial No. 195,341.

To all whom it may concern:

Be it known that I, IRVING A. WESTON, of Syracuse, in the county of Onondaga and State of New York, have invented a certain 5 new and useful Improvement in Massage Instruments, of which the following is a specification.

The main object of my invention is to provide a simplified form of power-driven massage instrument or apparatus for mechanically performing the various operations which are useful in massage treatments.

It consists in a novel arrangement of parts in simple yet efficient form adapted so that 10 the length of stroke or degree of vibration given to the pulsator may be regulated at the will of the operator.

Referring to the accompanying drawings, Figure 1 is a longitudinal section of massage 20 instrument constructed according to my invention. Fig. 2 is a transverse section of same on lines X-X of Fig. 1. Fig. 3 is a view of the main shaft detached. Figs. 4, 5, 6, and 7 are details of the parts used, hereinafter more fully described.

In carrying out the objects of my invention I provide a cylindrical metal case *a*, with a radial tubular extension *b* near one end of said casing *a*, constituting a handle by which 30 the instrument is manipulated, and is formed with a lengthwise opening therethrough from end to end, one end, opposite to that near which the tubular extension *b* is located, being smaller than the opposite end and is 35 closed by a cap *c*, while the larger end of the casing is closed by a cap *c'*.

The inner end of the tubular extension *b* communicates with the interior of the casing *a*, and in this extension is guided a 40 reciprocatory plunger *e*, having a reduced outer end which is guided in a suitable screw-cap fitted in the outer end of the tubular extension *b* and adapted to support a beater *d*, the latter being fitted upon the 45 reduced end *f* of the plunger *e* and is therefore reciprocated radially by said plunger in a manner presently described. The inner end of this plunger *e* is pivoted at *e'* to an oscillatory reciprocatory but non-rotatable 50 ring *f'*, which is guided in its movement between a fixed shoulder *m*, forming a part of the case *a*, and an adjustable annulus *m'*, the latter being located between the inner end of the cap *c'* and an adjacent face of the ring *f'* 55 and is therefore held in place and adjusted by a cap *c*. This ring *f'* has an opening there-

through from end to end axially of the casing *a*, the inner end of the opening being smaller than its outer end and is formed with a partially-spherical bearing-face, in which is seated a ball member *g*, and the outer end of the ring *f'* is threaded interiorly and receives a suitable screw-bushing. (See Fig. 5.) This is also provided with a partially-spherical bearing-face forming a continuation of the inner spherical bearing-face of the ring *f'* and serving to retain the ball *g* within the ring *f'*, at the same time to permit said ball to be removed and reinserted through the larger open end of the ring *f'*. The opening in the 60 end of the casing in which the cap *c* is fitted is slightly larger than the annulus *m'* and ring *f'* to permit these parts to be readily placed in operative position or removed from within the casing.

The interior bore of the casing *a* between the annular shoulder *m* and cap *c* is preferably cylindrical, and in it is fitted with an easy sliding fit a sleeve *j'*. This is of considerably less length than the distance between the annular shoulder *m* and inner end of the cap *c* to permit said sleeve to be moved endwise or axially a limited distance for a purpose presently described, such endwise movement being effected through the medium of a suitable handpiece *K*, which is screwed in the inner end of the sleeve *j'*, as best seen in Fig. 1, and projects outwardly through a slot *k'* in the casing *a*, said slot *k'* being of greater length than the diameter of 75 the handpiece *K* which plays in said slot and, together with the sides of the slot, prevent rotation of the sleeve *j'*. This sleeve *j'* has a central lengthwise bore, in which is journaled a rotary shaft *h*, having sliding 80 connection with the adjacent end of the flexible driving-shaft *i*, as best seen in Fig. 1.

The end of the shaft *h* nearest the ring *f'* is enlarged at *o* to a greater diameter than the interior diameter of the sleeve *j'* and abuts 85 against the adjacent end of said sleeve, while the opposite end of said shaft is reduced in diameter and receives a suitable annulus or collar, which is also of larger diameter than the bore in which the shaft *h* is journaled and abuts against the adjacent end of the sleeve *j'*, said collar being held in place by suitable lock-nuts *s*, which in turn are screwed upon the adjacent threaded portion *w* of the shaft *h*, as best seen in Fig. 1.

The spindle *j* has one end rigidly united to the adjacent face of the annular enlargement

o at one side of its axis of rotation, as best seen in Figs. 1 and 3, and projects endwise from said annular enlargement in the incline plane at an angle with and to the opposite 5 side of said axis of rotation, and its free end is journaled in a central opening in the ball *g*, so that by moving the shaft *h* its angular spindle *j* projects endwise so as to bring the intersecting point of the axes of the shaft *h* 10 and spindle *j* nearer to or farther from the center of the ball *g*, the latter causing the ring *f'* and plunger *e*, together with the beater *d*, to reciprocate through varying axial distances, which is the primary object sought.

15 It is evident from the foregoing description that the sleeve *j'* and its inclosed shaft *h* are locked against independent axial movement, although the shaft *h* is free to rotate and the sleeve is held against rotation by the 20 handpiece *k*.

I am aware that I am not the first to provide means broadly for reciprocating a beater, such devices being shown in the patents to Bihlmaier, No. 688,581, December 10, 25 1901, and also in Church, No. 743,147, November 3, 1903; but I believe I am the first to provide a rotating shaft with a rigid spindle projecting from one end of the shaft through a ball which is mounted in a partially-spherical bearing attached to a beater-plunger, and I also believe that I am the first 30 to move said shaft, together with its non-rotatable sleeve, endwise or axially for the purpose of moving the eccentric spindle through the ball.

In operation the shaft *h* and its eccentric spindle *j* are rotated through a medium of the shaft *i*, reciprocating motion being transferred to the plunger *e* through the medium 40 of the eccentric spindle *j*, ball *g*, and ring *f'*, and the degree of such movement is controlled by the handpiece *k* moving back and forth in the slot *k'* and imparting similar movement to the shaft *h*, sleeve *j'*, and eccentric spindle *j*, the axis of which latter is disposed at an angle with the axis of revolution of said shaft, with its free end at one side 45 of said axis, so that as the shaft *h* and spindle *j* are shifted back and forth the degree of the 50 movement of the beater is correspondingly varied.

What I claim as new, and desire to secure by Letters Patent, is—

1. In a massage instrument a casing constituting a handle having a lateral tubular extension, a plunger movable radially in said extension, a beater on the outer end of the plunger, a ring pivoted to the inner end of the plunger and provided with a partially-spherical inner bearing, a ball journaled in said bearing and provided with a central opening, a non-rotatable sleeve slideable endwise in the casing at right angles to the movement of the plunger, a handpiece attached to the sleeve and extended to the outside of the casing, a 60 rotary shaft journaled in said sleeve and movable endwise therewith and a spindle having one end rigidly united to the shaft and extending endwise therefrom at an angle with its axis and through the opening of the 65 ball.

2. In a massage instrument a casing, a rotary shaft movable endwise within the casing, means to move the shaft endwise, a spindle projecting from the end of the shaft at an angle with and across its axis, a non-rotatable ring, an oscillatory ball seated in the ring and provided with an opening receiving the free 75 end of said spindle, and a plunger attached to the ring and the beater on the plunger. 80

3. In a massage instrument, a casing constituting a handle and provided with a lateral tubular extension, a plunger movable radially in said extension, a beater on the plunger, a non-rotatable ring pivoted to one end 85 of the plunger, a ball journaled in the ring and provided with a diametrical opening, a rotary shaft movable endwise within the casing and provided with a rigid spindle projecting endwise at an angle with its axis and 90 slideable endwise with said shaft through the opening in the ball, and means for moving said shaft endwise.

In testimony whereof I have hereunto signed my name, in the presence of two attesting witnesses, at Syracuse, in the county of Onondaga, in the State of New York, this 24th day of February, 1904.

IRVING A. WESTON.
